IGNITER FOR INTERNAL-COMBUSTION ENGINES

Edwin D. Chaplin, New York, N. Y., assignor to Harry B. Albert, New York, N. Y.

Application February 3, 1944, Serial No. 520,871

16 Claims. (Cl. 123—145)

1

This invention relates to igniters for internal combustion engines for controlled timing of ignition of explosive gaseous mixtures and more particularly to apparatus and devices for igniting such mixtures by the use of direct or alternating current and at low as well as high voltages by means of incandescent heaters of the high resistance and induced current types though it is noted that in some of the claims the invention is not limited to heaters utilizing any particular kind of current nor even to electric heaters.

One object of the invention is to provide an improved device or apparatus of this kind which retains a blanket of spent gases over a heating element to prevent ignition of fresh gases until the latter have been compressed to the degree necessary for efficient operation of the engine and which prevents contact of the gases with any heater wires.

Other objects of the invention are to provide an improved device of this kind which requires no moving parts, eliminates spark gaps and their attending corrosion and pitting, and is effective over a wide pressure range for a given requirement of electrical energy.

Since a large proportion of airplane troubles are due to spark failure resulting from sliding contacts or high voltage leakage it is also my object to provide a device which may form a part of an ignition system having no moving contacts and referred to later in the description.

Additional objects of the invention are to effect simplicity and efficiency in such apparatus and to provide an extremely simple and compact device or apparatus of this kind which is economical, durable, and reliable in operation, and economical to manufacture and may be installed in a conventional cylinder head.

Still other objects of the invention will appear as the description proceeds; and while herein details of the invention are described in the specification and some of the claims, the invention as described in some of the broader claims is not limited to these, and many and various changes may be made without departing from the scope of the invention as claimed in the broader claims.

The inventive features for the accomplishment of these and other objects are shown herein in connection with an igniter which briefly stated, includes a cylindrical casing having the inner end thereof adapted to be screwed into the cylinder head of a motor and an igniter tube mounted in the outer end of the casing and spaced from the inner walls thereof to leave a dead air space as a heat insulator around the tube.

2

In the accompanying drawing showing, by way of example several of many possible embodiments of the invention,

Fig. 1 is a longitudinal sectional view, partly in elevation showing one form of the invention;

Fig. 2 is a fragmental side view showing one form of the igniter tube;

Fig. 3 is a fragmental side view showing another form of the igniter tube; and

Fig. 4 is a fragmental longitudinal sectional view partly in elevation showing another form of the casing.

In the drawing a substantially cylindrical socket member 10 provided with a bore 11 throughout has its inner end 12 of reduced diameter and provided with exterior threads 14 whereby said inner end may be threaded into a hole in the cylinder head 15 of an internal combustion engine. The exterior of the socket member adjacent said inner end is provided with lateral tool receiving faces 16 for screwing the inner end in said cylinder head. The outer end of the bore 11 is surrounded by an annular seat 19 surrounded by a wall 18 provided with internal threads 20 threadably receiving a hollow cylinder or thimble 21 of drawn steel or other suitable material in axial alignment with the socket member to form a casing, generally designated 17 the internal diameter of the cylinder being greater than that of the bore 11.

A cylindrical heating element generally designated as 22 comprising a non-fusible and non-combustible tube 24 is disposed within the hollow of the cylinder in axial alignment with the bore 11, the internal diameter of the tube preferably being equal to that of the bore. The exterior of the tube is wound with a coil of wire 25, the turns of the coil being electrically insulated from each other as by spacing if the wire is bare or by heat resisting insulation to prevent a short circuit between adjacent turns. The end portions 26 of the coil may be anchored in any suitable manner such as by passing them through holes 28 in lugs 29 cast on the tube. The inner end of the tube is disposed gas-tight against a packing ring 30 of asbestos or other suitable refractory material in the seat 19 while the outer end similarly engages a packing washer 31 of similar material urged inwardly by a plug 32 threaded in the outer end of the cylinder by means of threads 34. The length of the bore 11 and tube 24 and the thickness and inside diameter of the washer determine the volume of the space receiving the gases forced from the outer end of the cylinder and consequently the extent to which incoming explosive

mixtures will enter the igniter when they are compressed. Varying the thickness of the washer adjusts this space. For some mixtures better results would be obtained by the use of a thin washer while for other mixtures a thick one would serve better. The plug may be provided with a tool receiving opening or slot 35.

The cylinder is preferably provided with a pair of holes 38 in its mid-section through which pass bolts 39 having wide heads 40 welded to the wire end portions 26. Refractory insulating packing 41 surrounds the shank of the bolt and hard refractory insulating washers 42 at each end engage the packing. An outer nut 44 on the bolt draws the head and washers tightly against the 10 bolt thereby forming a gas-tight fit, the bolts being insulated from the cylinder. Conducting leads (not shown) may be connected to the 15 screws in any well known manner. If desired, one of the ends of the coil may be grounded so that only one bolt will be required. The plug 32 may be made integral with the cylinder 21 if the 20 cylinder and socket 10 are separate and the socket member and cylinder may be integral if the plug is separate. An annular space 45 is provided between the heater and the internal 25 walls of the cylinder both to allow space for the mounting of the bolts and to insulate the heater from the cylinder. The gas therein is stagnant 30 since the packing 30 and 31 and tube are substantially impervious.

In one form of the invention the tube or support 24 may be of refractory insulating material such as silicon carbide or fused alumina, otherwise known to the trade as Carborundum and 35 Alundum. If desired, the tube, as the 24a (Fig. 2) may be provided with an external helical groove 46 in which bare high resistance wire 25a is wound.

In another form of the invention the supporting member may comprise a tube 24b (Fig. 3) of conducting material such as copper or bronze as at Fig. 3 and the coil may be of coarse insulated low-resistance wire 25b so that for a given length of the supporting member the number of ampere-turns may be large. Current supplied to this form of the coil is preferably alternating or high frequency current so that eddy currents will be induced in the tube 24b and thereby cause it to heat up to ignition temperature. The tube 24b may be of magnetic material such as steel or iron so that heat is developed in the tube not only by means of eddy currents but by hysteresis losses in the form of heat when alternating current is used. When a tube of conducting material is used it is preferable to provide a sheath 49 of asbestos or other suitable refractory insulating material intermediate of the tube and coil for thermal insulation of the wire from the conducting tube as well as for electrical insulation. The tube 24b serves as a one-turn secondary of an induction heater while the coil of wire wound on the tube but insulated therefrom acts as the primary winding. Alternating current applied to the coil or primary winding induces a current to flow in the tube 24b so that the latter is heated by induction to a temperature sufficient to cause ignition of the fuel mixture. Since the tube 24b is of material such as copper or bronze any heat developed in it is rapidly conducted to the inner face of the tube to heat the gases or fuel mixture thereat.

Advantages of alternating current operation of the device are due in part to the fact that

the current can be supplied by alternators having permanent magnet rotors so that no brushes are required throughout the entire ignition system. Hence with my ignition device it is possible to eliminate all sliding contacts and air gaps which account for the great majority of ignition and motor failures. Furthermore my igniter may be operated at low voltages so that current leakages due to moisture on insulators, or moisture laden air between conductors, while a serious problem in conventional high tension ignition, are practically nil in my system.

The tube substantially prevents circulation of gases in the gas space to and from the major portion of the bore and the combustion zone so that the coil is not subjected to contact with fresh cool gases and the gas within the space acts as a heat insulating blanket to keep the heater hot and the thimble 21 cool.

The tube 24a may be of silicon carbide or alumina so as to be highly resistant to heat and at the same time be mechanically strong to withstand pressure differences set up between the gas space exterior and interior of the tube. In addition alumina acts as a catalyst for the transformation of hydrocarbon fuels to forms having a lesser tendency to knock.

In still another form of the invention as shown in Fig. 4, the casing 17a, is preferably integral and provided with only one terminal bolt hole 38a through which passes the bolt 39 as shown in Fig. 1. The heater 22 disposed gas tight against the ring 30 within the hollow portion of the casing is similar to that shown in Fig. 1. A washer 31a of refractory gas tight packing is disposed against the outer end of the heater followed by a disk of hard refractory material such as silica, alumina, or silicon carbide.

One of the end portions of the coil passes 40 through small registering holes 51 and 52 in the washer and disk respectively, thence in a radial groove 54 in the outer face of the disk from the hole 52 to the central portion of the disk. Carborundum cement or other suitable material may 45 be employed to prevent gas leakage through the hole 51. A cap 32a provided with a central recess 54 and terminal bolt hole 55 is threaded onto the outer end of the casing by means of threads 34a so that the disk is urged inwardly to clamp the 50 heater between the ring and washer. The cap is preferably built up with a boss about the hole 55 and the latter fitted with a terminal bolt 56 in the manner described of bolts 39 and the coil end 26a welded thereto.

In operation when the motor cylinder is cleared of exhaust gases the purging of gases from the bore of the casing is not complete and spent gases remain therein. Consequently when an ignitable fuel mixture is drawn or injected into the engine cylinder the spent gases prevent the combustible mixture from coming in contact with the heater until the fuel gases are compressed during the compression stroke and the spent gases are forced to the outer end portion of the thimble 21. By varying the capacity of the outer end portion of the bore by means of the plug 32 and washer 31 the time of contact between the fuel gas and the heater with respect to piston position can be varied to give the best operating position. Ignition takes place when a fuel mixture of proper composition is raised to its ignition temperature by heat of compression and heat supplied to the mixture by the heater tube.

The invention claimed is:

1. An igniter for gaseous mixtures, said igniter

comprising a casing; a conductive secondary core therein and adapted to be exposed to the gases; a primary coil of wire inductively coupled with the core so that a flow of alternating current in the primary coil will induce a current in the core to heat the latter; and means for substantially preventing the gases from coming in contact with the coil and wire.

2. An igniter for gaseous mixtures comprising a substantially cylindrical casing closed at its outer end and provided with a bore; a tube of hard refractory insulating material in the outer end of the bore; the interior of the bore being adapted to be exposed to the gases; a coil of high resistance wire wound on said tube; means for connecting the coil to a source of current and means for substantially excluding said gases from contact with the wire.

3. In combination, a substantially cylindrical casing closed at its outer end and provided with a bore, the casing having the inner end thereof of reduced diameter and provided with exterior threads whereby said inner end may be threaded into a hole in the cylinder head of an internal combustion engine; the exterior of the casing adjacent said inner end being provided with lateral tool receiving faces for screwing the inner end in said cylinder head; said bore being of decreased diameter toward the inner end of the casing to form an annular seat; a heated tube within the outer end portion of the bore in axial alinement with the inner end thereof and in gas tight engagement with said seat; the outer portion of the bore of the casing being of further sufficient diameter to receive said tube and to form a tubular gas space between the tube and the inner walls of the casing; and gas-tight means between the outer end of the tube and the interior wall of the closed end of the casing to substantially prevent passage of gases to and from the gas space.

4. An igniter comprising a substantially cylindrical socket member provided with a bore throughout, said bore being of increased diameter toward the outer end of the casing to form an annular seat; a thimble having its inner end threaded into said seat and closed at its outer end; a tube of silicon carbide in the thimble and axially alined with the bore and engaging the central portion of the seat; a coil of high resistance wire wound on said tube; the internal diameter of the thimble being of sufficient diameter to receive said coil and to form a tubular gas space between the coil and the inner walls of the thimble; the thimble being provided with radial holes; conducting bolts in said holes and welded to the end portions of said wire; packing between said bolts and the walls of said hole; a washer of refractory insulating material disposed gas-tight against the outer end of said tube; and a plug threaded into the outermost end portion of the thimble and engaging the washer.

5. In combination, a substantially cylindrical socket member provided with a bore throughout, said bore being of decreased diameter toward the inner end of the casing to form an annular seat; a thimble closed at its outer end and having its inner end threaded into said seat; a tube of fused alumina in the thimble and axially alined with the bore and engaging gas-tight the central portion of the seat; the hollow of the tube being substantially continuous with the inner end of the bore; a coil of high resistance wire wound on said tube; the internal diameter of the thimble being of sufficient diameter to receive said

coil and to form a tubular gas space between the coil and the inner walls of the thimble; and means at the outer end of the thimble to substantially prevent passage of gases to and from said gas space and the interior of the tube.

6. An igniter comprising a cylindrical casing provided with a bore of increased internal diameter at the outer end portion to form an annular seat therein; an electrical heater disposed in the outer end portion of the bore and gas tight against the seat and having wire end portions; refractory packing loosely received in the end portion of the bore and disposed gas tight against the outer end of the heater; a disk of refractory insulating material in the bore and disposed gas-tight against the outer face of the packing, the disk being provided with a radial groove in the outer face thereof; one of the wire end portions passing gas tight through the outer marginal portion of the packing and the disk and extending in the radial groove to the center of the disk; a cap mounted on the outer end of the casing; a terminal bolt passing gas-tight through the cap and insulated therefrom, the head of the bolt being recessed in the inner side of the cap, the inner face of the cap and said head engaging against the outer face of the disk and the wire end portion welded to the head.

7. An ignition device comprising a substantially cylindrical socket member provided with a bore throughout, said bore being of increased diameter toward the outer end of the casing to form an annular seat; a thimble having its inner end threaded into said seat and provided with radial holes; packing in the seat; a tube of refractory insulating material in the thimble and axially alined with the bore and engaging the packing in the seat; a coil of wire wound on said tube; the internal diameter of the thimble being of sufficient diameter to receive said coil and to form a tubular gas space between the coil and the inner walls of the thimble; conducting bolts in said holes and welded to the end portions of said wire; packing between said bolts and the walls of said hole; a washer of refractory insulating material on the outer end of said tube; and a plug threaded into the outermost end portion of the thimble and engaging the washer.

8. A device as in claim 7 and having a metallic tube within said tube of refractory insulating material.

9. An ignition device comprising, in combination, a substantially cylindrical casing provided with a bore throughout, the casing having the inner end thereof of reduced diameter and provided with exterior threads whereby said inner end may be threaded into a hole in the cylinder head of an internal combustion engine; said bore being of increased diameter toward the outer end of the casing to form an annular seat; a hollow cylindrical heating element within the bore in axial alinement with the casing and engaging gas-tight against said seat; a tube of refractory insulating material and engaging said ledge; a coil of wire wound on said tube; the outer portion of the bore of the casing being of sufficient diameter to receive said coil and to form a tubular gas space between the coil and the inner walls of the casing; a washer in the outer end of the casing and disposed gas-tight against the outer end of the tube and a hard refractory disk thereagainst, one end portion of said wire passing through the outer marginal portion of the disk and washer; a plug threaded in said bore to close the outer end of the casing.

10. An ignition device comprising in combination, a substantially cylindrical casing provided with a bore throughout, the casing having the inner end thereof of reduced diameter and provided with exterior threads whereby said inner end may be threaded into a hole in the cylinder head of an internal combustion engine; said bore being of increased diameter toward the outer end of the casing to form an annular seat outer of the engine cylinder; a tubular cylindrical heating element within the outer end of the bore in axial alignment with the casing and engaging gas tight against said seat, said heating element comprising, a tube of refractory insulating material; a coil of wire wound on said tube; electrically conducting means connected to the ends of said coil the outer portion of the bore of the casing being of increased diameter to receive said coil and to form a tubular gas space between the coil and the inner walls of the casing; a washer in the outer end of the casing and disposed gas-tight against the outer end of the tube; and closure means on the outer end of the casing engaging against the outer face of the washer for closing off the hollow of the tube from the atmosphere exterior of the engine cylinder and ignition device.

11. An ignition device comprising in combination, a substantially cylindrical casing provided with a bore throughout, the casing having the inner end thereof adapted to be mounted in a hole in the cylinder head of an internal combustion engine; a hollow cylindrical electrical heating element within the outer end of the bore the bore thereby providing a deep pocket where spent gases tend to remain stagnant during operation of the engine; the outer portion of the bore of the casing being of increased diameter to receive said element and to form a tubular gas space between the element and the inner walls of the casing; and closure means on the outer end of the casing for closing off the bore from the atmosphere exterior of the engine cylinder and ignition device.

12. An ignition device comprising in combination, a substantially cylindrical casing provided with a bore throughout, the casing having the inner end thereof adapted to be mounted into a hole in the cylinder head of an internal combustion engine; an electrical heating element within the outer end of the bore; said heating element comprising a support of fused alumina and a coil of wire wound on said support, the support being exposed to the fuel gases in the engine, and closure means on the outer end of the casing for closing off the bore from the atmosphere exterior of the engine cylinder and ignition device.

13. An ignition device comprising in combination, a substantially cylindrical casing provided with a bore throughout, the casing having the inner end thereof adapted to be mounted in a
